DESIGN FOR A NECKTIE

David Margolis, New York, and Sol Weisblatt,
Brooklyn, N. Y.

Application October 9, 1947, Serial No. 141,816

Term of patent 7 years

(Cl. D3—16)

To all whom it may concern:

Be it known that we, David Margolis and Sol Weisblatt, both citizens of the United States, residing at New York and Brooklyn, New York, in the county of New York and Kings and State of New York, have invented a new, original, and ornamental Design for a Necktie, of which the following is a specification, reference being had to the accompanying drawing, forming a part thereof.

In the drawing the figure is a front elevational view of the front portion of a necktie, showing my new design.

The opposite end of the necktie is conventional.

I claim:

The ornamental design for a necktie, as shown and described.

DAVID MARGOLIS.
SOL WEISBLATT.
